UNITED STATES PATENT OFFICE.

WILLIAM EDWARD BASSETT, OF FRESNO, CALIFORNIA.

SELF-LAYING TRACTION-TRACK.

1,144,284.

Specification of Letters Patent. Patented June 22, 1915.

Application filed August 19, 1914. Serial No. 857,494.

To all whom it may concern:

Be it known that I, WILLIAM E. BASSETT, a citizen of the United States, and a resident of Fresno, in the county of Fresno and 5 State of California, have invented a new and Improved Self-Laying Traction-Track, of which the following is a full, clear, and exact description.

My invention relates more particularly to 10 endless self-laying tracks for the wheels of traction vehicles.

The object of the invention is to improve devices of the indicated character, to the end that efficiency in operation may be promoted, as well as simplicity of construction and convenience in the assembling and renewal of the parts.

The invention will be particularly explained in the specific description following.

Reference is to be had to the accompanying drawings forming a part of this specification, in which similar characters of reference indicate corresponding parts in all the views.

Figure 1 is a side elevation of the traction track constructed in accordance with my invention, showing the application of the same to a pair of vehicle wheels; Fig. 2 is a side elevation of two adjacent links, illustrating the manner of assembling the same; Fig. 3 is a side elevation of two assembled links, together with a special shoe employed in connection with the links to form the tread surface; Fig. 4 is a cross section on the line 4—4 of Fig. 3; Fig. 5 is a top plan view of one of the links; Fig. 6 is a top plan view of one of the shoes; Fig. 7 is a fragmentary end view of a link employed to couple the ends of the chain; and Fig. 8 is a side elevation of the link shown in Fig. 7.

In constructing a track in accordance with the illustrated example, a series of links 10 are provided, and each link is formed at one end with laterally spaced hooks 11. At the 45 opposite end each link 10 is formed with a cross bar 12, to engage the hooks 11 of an adjacent link. The bar 12 is supported from the adjacent end of the link by a web 13 disposed centrally of the said bar, whereby the 50 ends of the bar project laterally in the form of hinge pintles. At the outer sides the hooks 11 present inclined sockets or slots 14, which are disposed at an inclination to the

longitudinal direction of the length. The upper side of each link has along the sides 55 thereof, ribs 15, thereby producing a channel at the upper side, at the inner side or bearing surface of the link, to receive a wheel or wheels A.

The form and arrangement of the respective members at the ends of the link, necessitate that the links be disposed at an angle to each other in connecting one link to the other so that when the links are brought into alinement, accidental separation of the link 60 is not possible. To effect the described connection of the links, the ends of the ribs 15 adjacent to the pivot bar 12 overhang the ends of the latter and are spaced therefrom, and curved surfaces 17 are produced on the 70 links at the outer side of the said projecting members of the ribs, the curves being struck from the center of the bar 12. The exterior surfaces of the hooks 11 are similarly curved. The slots 14 have inclined rear walls 18, 75 the inclined surface being continued across the link, as indicated in Fig. 5; also the upper surfaces of the outer ends of the ribs 15 are beveled, as at 19.

With the described construction the links 80 are assembled by bringing them to an angle with each other, as in Fig. 2, so that the slots 14 will be alined with the webs 13 supporting the pivot bars 12, said webs being inclined to the longitudinal direction of the 85 links. The pivot bars 12 of one link may now be entered in the slots 14 of the adjacent link, whereupon the respective links are brought into longitudinal alinement as in Fig. 3, which brings the backs of the hooks 90 11 beneath the curved overlapping surfaces 17, so that a separating movement of the links is not possible.

In connection with the links as described, I employ a separate shoe 20 beneath each 95 link. Said shoe is formed at the inner side with spaced lugs 21 which receive a transverse pin 22, said pin passing also through a transverse rib 23 on the outer side of the link 10. The said rib 23 is received in a depression 24 produced in the inner side of the shoe 20 between the lugs 21. The pins 22 are shown as headed at one end and fastened at the other end by cotter pins, one of which is indicated in Fig. 4. The lugs 21 and the 100 rib 23 are disposed on the shoe and link, be-

tween the ends thereof, preferably at the center. The shoes 20 present end surfaces constituting the tread or traction surface of the track, and they are so formed relatively 5 to the ends of the links, and the pivot elements of the latter, that the shoes close the slots 14 of the links, with the purpose of excluding dirt and grit from the joints. The end of each shoe presents lateral members 10 20^a (see Figs. 1 and 3) overlapping the joints of the links, and the inner surfaces of these overlapping members 20^a are concaved, as at 20^b, the curves of which are struck from the center of the pivot bars 12, and 15 thus conform to the exterior surfaces of the hooks 11, to permit the proper relative movement of the links and shoes as the endless track travels around the wheels A. The bevel surfaces 19 permit the shoes to assume 20 the necessary angles to each other in turning around the wheels.

It will be clear from the above description that for the disconnection of a particular link, a shoe 20 must be removed, and 25 then the links brought to a position at a sharp angle to each other to permit a separating movement of the links. Thus the accidental disconnection of the links is made impossible, while repair or renewal of a link 30 may be effected with facility and despatch. A special link is provided for the meeting ends of the rail after the assemblage of the links 10, the special link being necessary, as the connecting link must be in longitudinal 35 alignment with the adjacent links in forming the final pivot or hinge joint of the chain, since otherwise a looseness of the chain on the wheels would result. The special link, designated by the character 10^a 40 is shown in Figs. 7 and 8. At one end it is provided with hooks 11 identical with those on the links 10. The link 10^a furthermore has the ribs 15 formed as described. The end of the link 10^a however, 45 opposite the hooks 11, instead of having a hinge bar 12 presenting laterally projecting hinge members and a web 13, is provided with a hinge member or knuckle member 12^a disposed centrally thereon, and is 50 adapted to be received in the space 11^a (Fig. 5) between adjacent hooks 11; thus a link 10 and a link 10^a may be brought together by a longitudinal movement thereof and with the links in the same plane until 55 a transverse bore 12^b (Fig. 8) in the knuckle member 12^a, registers with the slots 14 in a pair of hooks 11. The knuckle 12^a and hooks 11 are now united by a hinge pin 26 (Fig. 1) corresponding with the pins 22 60 and fastened by a cotter pin 28^a.

Having thus described my invention, I claim as new, and desire to secure by Letters Patent:

1. In a traction chain, a series of links,

each link being formed at one end with 65 hinge elements in the form of hooks, said hooks presenting open slots, the opposite end of each link presenting hinge members adapted to enter the slots at the opposite end of an adjacent link and be engaged by 70 the hooks of the latter, and detachable shoes on the links, one end of the shoe forming the closure of the slots at an end of the link and overlapping, at the opposite end, the adjacent hinge elements, and positioned to 75 close the slots in the next link.

2. In a traction chain, links, and detachable shoes, the links having at one end, 80 hooks presenting slots at the under side inclined to the longitudinal direction of the links, and a hinge bar at the opposite end of each link presenting lateral hinge pintles, the shoes overlapping the links and closing the slots in adjacent links.

3. In a traction chain, links having at one 85 end hinge elements in the form of hooks located near the sides of the link, the backs of the hooks being rounded, and said hooks presenting slots at an angle to the longitudinal direction of the links, the opposite 90 end of each link having a hinge bar presenting laterally projecting pintles received in the slots of an adjacent link, and shoes having ends overlapping the hinge members of the links and closing the slots of the respective 95 links.

4. In a traction chain, a series of pivotally connected links having ribs at the inner side forming a channel for wheels, and having transverse ribs at the outer sides, shoes 100 on the links at the outer sides thereof, flanges on the shoes between which the ribs on the links are received, and a transverse pin uniting the said ribs and flanges, the ends of the shoes overlapping the pivots of 105 the links.

5. In a traction chain, links formed at one end with hooks and at the opposite end with 110 outwardly projecting hinge pintles adapted to be received in the hooks of an adjacent link, the said hooks being rounded on the exterior surface and presenting slots for the entrance of the pintles, the ends of the links adjacent to the pintles overlying the latter and presenting opposed rounded surfaces, 115 the said rounded surfaces being spaced from the pintles to receive the hooks of an adjacent link, and shoes detachably secured to the links at the exterior and having overlapping members curved to conform to the 120 curvature of the hooks.

6. In a traction chain, a series of links each formed at one end with hooks rounded on the outer surface and presenting slots inclined to the longitudinal direction of the 125 links, pintles on the opposite ends of the links receivable in said slots of adjacent links, a joining link having at one end hooks

corresponding with those of the first mentioned links, and at the opposite end a knuckle member fitting between the hooks of one of the first mentioned links, and a 5 transverse pin pivotally connecting the said knuckle member and the adjacent hooks.

In testimony whereof I have signed my

name to this specification in the presence of two subscribing witnesses.

WILLIAM EDWARD BASSETT.
